United States Patent Office

Des. 177,775
Patented May 22, 1956

177,775

FOOD MIXER

Henry J. Talge, Kansas City, Mo., assignor to John C. Hockery, trustee, Kansas City, Mo.

Application December 15, 1955, Serial No. 39,338

Term of patent 14 years

(Cl. D44—1)

Fig. 1.

Fig. 2.

Fig. 1 is a perspective view of a food mixer embodying my new design, and

Fig. 2 is an elevational view of same, showing the opposite side thereof.

The essential features of my design reside in portions shown in solid lines, the portions shown in dotted lines being for purposes of illustration only.

I claim:

The ornamental design for a food mixer, as shown and described.
